EX

OR D 16,810

No. 16,810.

Patented July 20, 1886.

DESIGN FOR A RUG.

SPECIFICATION forming part of Design No. 16,810, dated July 20, 1886.

Application filed June 19, 1886. Serial No. 205,727. Term of patent 3½ years.

UNITED STATES PATENT OFFICE.

ADOLPH PETZOLD, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 16,810, dated July 20, 1886.

Application filed June 19, 1886. Serial No. 205,727. Term of patent 3½ years.

To all whom it may concern:

Be it known that I, ADOLPH PETZOLD, a citizen of the United States, and a resident of Philadelphia, Pennsylvania, have invented and produced a new and original Design for Rugs, of which the following is a specification, reference being had to the accompanying photographic illustration, to which reference is made.

10 In the illustration, A is a rectangular border, inclosing a large panel, B. The latter is ornamented with a peacock, C, with traile tail, a flight of steps, D, and balusters D'. Above and to the left of the balusters is a 15 dense mass of leaves and flowers, prominent among which are the large cabbage-shaped flowers E E. In the lower right-hand corner is a cluster of large begonia-leaves, F, as shown, and fancy flower G, and in the upper 20 and right-hand corner and side a large cluster of leaves, H.

The leading and essential features of my design are the peacock with the traile tail, the balusters and steps, large flowers E E, begonia-leaves F in the lower right-hand corner, 25 cluster of leaves H in the upper right-hand corner, and the surrounding rectangular border.

What I claim is—

As a design for rugs, the middle feature of 30 a peacock with traile tail, the balusters and steps, large flowers E E, begonia-leaves F in the lower right-hand corner, cluster of leaves H in the upper right-hand corner, and the surrounding rectangular border, substantially 35 as shown and described.

ADOLPH PETZOLD.
